CLAIM

The ornamental design for a notebook computer having a textured surface as shown and described.

DESCRIPTION

FIG. 1 is a top-right rear perspective view of the notebook computer having a textured surface, shown in an open position;

FIG. 2 is a top view thereof, shown in a closed position;

FIG. 3 is a bottom view thereof;

FIG. 4 is a front view thereof;

FIG. 5 is a rear view thereof;

FIG. 6 is a left side view thereof;

FIG. 7 is a right side view thereof; and,

FIG. 8 is an enlarged view of portion “8” in FIG. 2 of the textured surface of the notebook computer having a textured surface.

The grayscale shading applied to the drawings indicate contours and surface texture. The dark rectangles in FIGS. 1, 2, and 8 depict debossed portions disposed in a staggered manner on the textured surface of the claimed design.

The evenly-dashed broken lines in FIGS. 1-7 depict portions of the notebook computer having a textured surface that form no part of the claimed design. The dash-dot broken lines indicate the areas of the enlarged detail views and form no part thereof.

The broken lines in FIGS. 1-7 depict portions of the notebook computer having a textured surface that form no part of the claimed design. The grayscale shading applied to the drawings indicate contours and surface texture. The dark
